UNITED STATES PATENT OFFICE.

JOSEPH E. BURNS, OF CANASTOTA, NEW YORK.

ARTICLE-SUPPORTING DEVICE.

1,272,772.

Specification of Letters Patent. Patented July 16, 1918.

Application filed October 26, 1917. Serial No. 198,589.

To all whom it may concern:

Be it known that I, JOSEPH E. BURNS, a citizen of the United States, and resident of Canastota, in the county of Madison, in the State of New York, have invented new and useful Improvements in Article-Supporting Devices, of which the following, taken in connection with the accompanying drawings, is a full, clear, and exact description.

This invention relates to certain improvements in article supporting devices, and is particularly adapted for supporting articles of glassware and the like for dipping in an acid or other solution.

It is well known that the finishing and polishing of cut glass articles is rendered more economical and more effective if after cutting the articles are immersed or dipped in a suitable acid solution, but in effecting this dipping operation it is essential that the acid should be kept from contact with the interior or uncut portion of the glass article and it is for effecting this dipping operation in a rapid, easy and efficient manner, and without exposing the uncut portions of the glass, that my device is peculiarly adapted and designed.

The main feature of the invention, in combination with the broad essentials of the device, relates to the construction of the immediate support for the article to be dipped, which support readily adjusts itself to the article to form an acid-tight joint and permits the dipping of numerous articles of various sizes and shapes with the same dipping device.

Other objects relate to the details of construction of the device, as will more fully appear from the following detailed description, taken in connection with the accompanying drawings, in which—

Figure 1 is a top plan view of a device embodying features of this invention.

Fig. 2 is a cross section, taken on line 2—2, Fig. 1, illustrating in addition a means for producing suction.

Fig. 3 is a view of a form of device slightly different from that shown in Fig. 1.

Fig. 4 is a cross section taken on line 4—4, Fig. 3.

Fig. 5 is a sectional view of a form of device in which the vacuum is automatically retained within the article after the vacuum producing means has been cut off.

The invention, as shown in Figs. 1 and 2,

comprises a hollow casing or chamber —1— from which radiate a series of tubes or pipes —2— to which vertical tubes —3— are connected by means of unions —4—, the unions 60 in this instance being closed except for the communication between tubes —2— and —3— as by plugs —5—. Other forms of union than those shown may be used.

Preferably, the upper end of the vertical 65 tubes —3— are externally threaded for the reception of pairs of washers —6— and —7— held in place by a suitable nut —8— having a threaded relation with the tube. The washers may also, if desired, have a 70 similar threaded relation with the tube or may be slidably engaged therewith.

Between the washers —6— and —7— on each tube —3— is positioned the base portion of a supporting cup —9— for the article to be dipped. These cups may be formed of rubber or other suitable material, preferably of a resilient flexible nature. The cups are of hollow conical formation with an upper flat wall —10— of circular form 80 and having a central opening through which the tubes —3— extend, and a side wall —11— integral with said upper wall and circular in cross section and flaring downwardly and outwardly therefrom. The wall 85 —11— is of considerable thickness for the purpose of giving considerable rigidity to this portion of the structure, while the side wall at its point of connection with the upper wall is of substantially the same thickness 90 as said upper wall. The thickness of said side wall decreases gradually from said point of connection to the free edge of the cup so that the free edge of the cup is of considerably greater flexibility than the portions nearer the upper wall —10—, such 95 flexibility being a feature in addition to the resilient nature of the material and gradually increasing downwardly from the wall —10— to the free edge of the cup, rendering 100 the cup peculiarly efficient in the formation of a liquid-tight joint with articles of various sizes and shapes when suction is applied to withdraw air from the article as hereinafter described.

In the specific illustration of Figs. 1 and 2, six radiating tubes —2— are shown and six cups for supporting articles to be dipped, but it will be readily apparent that the number of radiating tubes and cups, as well as 110 the size and arrangement of the same, may be varied.

A suitable pipe —12— is preferably connected to the chamber —1— and may extend, as shown, vertically therefrom and be provided with a horizontally extending portion —13— constituting a handle, the portion —13— adapted to be attached to any suitable vacuum producing device, such as the device —14— herewith shown, which is adapted for use with an ordinary water faucet, a valve —15— being interposed in the connection for the purpose of retaining the vacuum in the article to be dipped during the dipping operation, and when the vacuum producing device is not operating.

15 The articles to be dipped are placed upon the cups —9— so that their edges rest upon the tapered side walls of the cups. The air is then withdrawn from such articles through the tubes —3—, the tubes —2—, and 20 the chamber —1—, to draw the articles firmly into liquid-tight engagement with the cups, the resiliency and the flexibility of the cups acting to render the liquid-tight engagement absolute and perfect. The vacuum 25 may then be retained in the communicating portions of the device in any suitable way, as by a shut-off or valve —15— and the dipping operation may then be effected without any danger of the articles falling 30 from the dipping device or any acid coming in contact with the interior of the articles.

In Figs. 3 and 4, I have shown a slightly modified form of device, in that the chamber —16— is of considerably larger size 35 than the chamber —1— and the vertical tubes —17— in construction and operation similar to the tubes —3— are mounted directly upon the chamber —16— and may, as shown, have a threaded relation therewith. The construction of the cups —9— 40 and the method of mounting the same upon the tubes —17— is the same as that shown in Figs. 1 and 2.

For the purpose of forming a handle to 45 be grasped by the operator in using the device, a rod —18— is connected to the wall of chamber —16— and may, as shown, extend substantially parallel with the pipe —19— which functions in the same manner 50 as pipe —12—. The upper end of pipe —19— is connected by a union —20— to a valve casing —21— which in turn may be connected by flexible hose —22— to a device for producing vacuum. The union 55 —20— is a three-way union and is connected by plug —23— to the upper end of rod —18—, the plug —23— constituting a gripping handle. It is obvious, however, 60 that various other constructions may be used and that modifications of the exact structure shown may be made, although the one illustrated is considered preferable.

In Fig. 5, each tube —17— is provided 65 with an automatic shut-off valve —24— mounted in a boss —25— formed in the

wall of chamber —16— and spring pressed to normally close the tube —17— but adapted to be opened by suction produced in chamber —16— with which the interior boss —25— communicates through a relatively small orifice —26—. The operation 70 will be readily understood.

When the vacuum in an article supported upon the cup —9— is greater or equal to the vacuum existing in chamber —16—, the valve —24— will remain closed to retain the article upon cup —9—. With this construction the valves —15— and —21— would not be essential.

It should be noted as a feature of great 80 importance that the cups —9— are supported entirely from the central portion of their upper walls and that their side walls are entirely free to flex and bend in contact with articles to be dipped, whether the same 85 are mechanically forced thereon or drawn into liquid-tight engagement therewith by the production of vacuum therein.

Although I have shown and described 90 specific constructions as illustrative of my invention and have set forth certain features as perhaps preferable in the embodiment shown, I do not desire to limit myself to the same except in so far as the details or preferred embodiments may be specifically set forth in the claims hereto appended.

What I claim is:—

1. In a device of the class described, a hollow casing, a tube in communication therewith, and a cone shaped cup supported 100 from its upper wall only by said tube.

2. In a device of the class described, a hollow casing, a tube in communication therewith, and a flexible cone shaped cup formed of resilient material and supported 105 from its upper wall only by said tube.

3. In a device of the class described, a hollow casing, a tube in communication with the interior of the casing, and a cone shaped cup having a cross wall and a tubular side 110 wall extending downwardly and outwardly from the cross wall, said cone shaped cup supported from its upper wall only by said tube.

4. In a device of the class described, a hollow casing, a tube in communication with the interior of the casing, and a cone shaped cup having a cross wall and a tubular side wall extending downwardly and outwardly from the cross wall, said cross wall provided 120 with an opening through which said tube extends, and said cone shaped cup supported from its upper wall only by said tube.

5. In a device of the class described, a hollow casing, a tube in communication with 125 the interior of the casing, a cone shaped cup having a cross wall and a tubular side wall extending downwardly and outwardly from the cross wall, said cross wall provided with an opening through which said tube extends, 130

- said cone shaped cup supported from its upper wall only by said tube, and means including parts positioned upon opposite sides of said cross wall for securing the cup to the 5 tube.
6. In a device of the class described, a hollow casing, a tube in communication with the interior of the casing, and a cone shaped cup having a cross wall and a tubular side wall extending downwardly and outwardly from the cross wall and decreasing in thickness downwardly from the cross wall, said cone shaped cup supported from its upper wall only by said tube.
- 10 7. In a device of the class described, a hollow casing, a tube in communication with the interior of the casing, and a cone shaped cup having a cross wall and a tubular side wall extending downwardly and outwardly from the cross wall and decreasing in thickness downwardly from the cross wall, said cross wall provided with an opening through which said tube extends, and said cone shaped cup supported from its upper wall 20 only by said tube.
- 25 8. In a device of the class described, a hollow casing, a tube in communication with the interior of the casing, a cone shaped cup having a cross wall and a tubular side wall extending downwardly and outwardly from the cross wall and decreasing in thickness downwardly from the cross wall, said cross wall provided with an opening through which said tube extends, said cone shaped cup supported from its upper wall 30 only by said tube, and means including parts positioned upon opposite sides of said cross wall for securing the cup to the tube.
- 35 9. In a device of the class described, a hollow casing, a tube in communication with the interior of the casing, and a cone shaped cup having a cross wall and a tubular side wall extending downwardly and outwardly from the cross wall and decreasing in thickness downwardly from the cross wall, said cross wall provided with an opening through which said tube extends, said cone shaped cup supported from its upper wall 40 only by said tube, and means including parts positioned upon opposite sides of said cross wall for securing the cup to the tube.
- 45 10. In a device of the class described, a hollow casing, a tube in communication with the interior of the casing, and a cone shaped cup having a cross wall and a tubular side wall extending downwardly and outwardly from the cross wall and increasing in flexibility as it extends downwardly from the cross wall, said cone shaped cup supported from its upper wall only by said tube.
- 50 11. In a device of the class described, a hollow casing, a tube in communication with the interior of the casing, a cone shaped cup having a cross wall and a tubular side wall extending downwardly and outwardly from the cross wall and increasing in flexibility as it extends downwardly from the cross 55 wall, said cross wall provided with an opening through which said tube extends, and said cone shaped cup supported from its upper wall only by said tube.
12. In a device of the class described, a cup for supporting an article to be dipped, said cup formed of resilient material and comprising a cross wall and a tubular side 60 wall secured to the cross wall and diverging outwardly as it extends therefrom, and means for supporting said cup with its side wall free to flex and bend inwardly.
13. In a device of the class described, a cup for supporting an article to be dipped, said cup formed of resilient material and comprising a cross wall and a tubular side 65 wall secured to the cross wall and diverging outwardly as it extends therefrom, and means for supporting said cup with its side wall free to flex and bend inwardly.
14. In a device of the class described, a cup for supporting an article to be dipped, said cup formed of resilient material and comprising a cross wall and a tubular side 70 wall secured to the cross wall and diverging outwardly and increasing in flexibility as it 75 extends therefrom.
15. In a device of the class described, a cup for supporting an article to be dipped, said cup formed of resilient material and comprising a cross wall and a tubular side 80 wall secured to the cross wall and diverging outwardly and decreasing in thickness as it extends therefrom.

In witness whereof I have hereunto set my hand this 19th day of October, 1917.

JOSEPH E. BURNS.
